UNITED STATES PATENT OFFICE.

DEYO JONES, OF DETROIT, MICHIGAN.

LUBRICATING DEVICE FOR LOCOMOTIVE-ROD-PIN CONNECTIONS.

1,310,531.

Specification of Letters Patent. Patented July 22, 1919.

Application filed January 12, 1918. Serial No. 211,514.

To all whom it may concern:

Be it known that I, DEYO JONES, a citizen of the United States, residing in Detroit, county of Wayne, and State of Michigan, have invented a new and useful Improvement 5 in Lubricating Devices for Locomotive-Rod-Pin Connections, and which is an improvement over the device now in use.

This invention relates to lubricating devices 10 for locomotive rod pin connections, and an object thereof is to provide an automatic device for feeding grease to the crank pin connection of locomotive drive wheels, and a further object is to provide a self- 15 feeding lubricating device actuated by movement of the locomotive rod to continuously feed grease to the rod pin connection during operation thereof. A further object is to provide a self-lubricating device of the character 20 stated in which the rate of feed may be increased or diminished as occasion may require, and an additional object is to provide a grease cup having a plunger adapted to be automatically screwed into the cup to feed 25 grease by operation of a sliding block actuated by the throw of the rod to which the device is attached. A further object is to provide means in a construction of the character 30 stated whereby, when the plunger has been turned practically to its limit downward in the cup, actuation thereof by the sliding block automatically ceases. These objects and the several novel features of the invention 35 are hereinafter more fully described and claimed and shown in the preferred form in the accompanying drawings in which—

Figure 1 is a vertical section of my improved device taken on line A—A of Fig. 2.

Fig. 2 is a horizontal section taken on line B—B of Fig. 1.

Fig. 3 is a section taken on line C—C of Fig. 1.

Fig. 4 is a similar section showing a different relationship of parts.

Fig. 5 is a detail of part of the feed control device.

Fig. 6 is a diagram showing the means for automatically releasing the feeding device.

Fig. 7 is a diagrammatic view illustrating the grease cup in position on the locomotive rod.

The usual grease cup heretofore employed on locomotive rods for lubrication of the 55 crank pin requires turning thereof by hand to feed grease to the bearing point and it

frequently happens that, especially on long runs, the crank pin bearing becomes overheated. This invention seeks to provide mechanism to continuously feed grease to a predetermined extent to the bearing during operation of the device, the rate of feed varying directly in accord with the rate of speed of travel of the locomotive. As shown in Fig. 7, the grease cup 1 is provided on the upper side of the locomotive rod 2 and a channel 3 is provided leading to the aperture 4 in the blocks for the crank pin of the driving wheel. As will be understood more clearly from Fig. 1, the grease cup 1 is provided with a threaded wall to receive the threaded plunger 5. It is to be noted that the rod 2 is provided with a recess 6 slightly greater in diameter with the diameter of the cup and of a depth at least equal to the thickness of the threaded portion of the plunger whereby the said plunger may be fully withdrawn from the cup into the said recess 6 and this recess may be provided by the addition of an apertured plate 7 on the upper surface of the rod 2, or may be provided by counter-boring the rod itself. The plunger 5 has a square stem 8 extending upwardly therefrom and on this plate 7 or directly on the upper face of the locomotive rod is positioned a case 9 preferably hinged at 10 on one side to the block 7 or to the rod 2 as the construction may be. This case is preferably formed of a body member having a base 11 a slight distance above which is provided a shoulder 12 to receive a plate 13 which provides a shallow chamber 14 between the plate 13 and base 11. Bosses 15 are provided between this base 11 and plate 13 at each corner, as will be understood from the drawings, threaded to receive the threaded end of the binding rod 16 which rod passes through the upper cover member 17 fitting in the upper end of the case and through the member 13 whereby both of the 100 covers are retained in positioning. The rod 16 is provided with a shoulder at the bottom engaging against the cover 13 and the head of the bolt engages against the cover 17. In the chamber 14 at the bottom of the case is provided a feed gear 18 having a squared central aperture for the plunger stem 8 and provided with a hub 19 of a length substantially equal to the depth of the case 14 retaining the gear in the desired position 105 vertically of the case. The large gear 18 is actuated through operation of a ratchet

wheel 20 shown in Fig. 2 and in bottom view in Fig. 5 from which it may be observed that the ratchet wheel is provided on the lower side with a single tooth 21 of a character to engage between the teeth of the feed wheel 18. This single tooth 21 moves the feed wheel one tooth each complete revolution of the ratchet wheel to which it is secured and of which it forms a part and the said wheel 18 is therefore moved slowly even with a comparatively rapid rotation of the ratchet wheel. The ratchet wheel as will be understood from Figs. 1 and 2, is operated by means of a spring-controlled pawl 22 pivotally mounted on a lever 23 which lever is pivoted to the shaft of the ratchet wheel mounted in the partition wall 13 and base 11 of the case. This lever 23 has a portion 24 extending upwardly at a right angle thereto through an arcuate slot in the plate 13 as indicated in dotted lines 30 in Figs. 3 and 4, and an elongated aperture 60 in a sliding block 25 between the cap plates 17 and the plate 13. This block and the case is to be understood as being positioned on the locomotive rod in such position that the rotation of the rod throws the weight backward and forward in the case and, to prevent the striking of the block against the sides of the case, buffers 26 and 27 are provided at opposite sides of the case against which the block engages. These may be of rubber or of any approved form to prevent the block from striking forcibly any unyielding part. For this latter purpose also the block should be cut out at each corner as indicated at 66 in Figs. 3 and 4 to prevent the block from striking the binding rods 16 at the corners of the case. The block is provided with a central aperture or slot 31 through which the plunger stem 8 projects allowing the block to move freely to its fullest extent. It will be seen that, as the locomotive rod is reciprocated the block will automatically be drawn forward and backward in the case and this movement of the block, due to the fact that the end 24 of the lever lies in a recess in the block turns the lever 23 on its axis on the shaft of the ratchet wheel 20. This causes the pawl to turn the ratchet wheel during movement of the lever to the left of Fig. 2, and each complete forward and backward movement of the block therefore actuates the ratchet 20 to a predetermined extent. The ratchet wheel is prevented from turning back with the ratchet 20 and the pawl 22 by means of a spring catch member 33 supported in the case. The movement of the block is limited by the buffers heretofore mentioned and, when these buffers are positioned as shown in full lines in Fig. 4, the block has a certain predetermined extent of movement and the feed of the plunger 5 is therefore at a predetermined rate relative to the revolution of the drive wheels of the

locomotive. If it be desired to increase the rate of feed, however, the buffer 27 may be moved to position shown in dotted lines in Fig. 4 by loosening the threaded nut 34 and repositioning the buffer as shown by dotted lines. In this position shown by dotted lines the buffer is opposite a notch 35 formed in one side of the block 25 allowing a greater movement of the block in the case and thus increasing the rate of speed of revolution of the ratchet wheel and consequently of the feed gear.

By thus controlling the movement of the feed gear by means of the locomotive rod, the grease is fed to the crank pin in a manner automatically corresponding with the rate of movement of the crank pin. That is—if the locomotive is operated at a high rate of speed, the grease is fed to a greater extent per unit of time than if it is operated at a slow rate of speed and the rapidity of feed per unit of time varies in accordance with the variation in speed, although the rate of feed for each complete movement of the locomotive rod is constant.

To prevent the feed wheel continuing to be turned when the plunger has reached its lowermost point of travel in the grease cup, I provide an automatic device for disengaging the ratchet from the feed wheel. This is shown somewhat in diagrammatic form in Fig. 6 and includes a vertical plunger 40 which has an angularly shaped lower end 41 terminating in the chamber 13. This end 41 lies in contact with the end of the pawl 22 shown clearly in Fig. 2 and, as is indicated at 22 in Fig. 6. The plunger is vertically movable in an aperture in the plate 13 and above this aperture the rod 40 is provided with a flexible spring member 42 tending to hold the plunger 40 in its uppermost position indicated by dotted lines in Fig. 6. The plunger is provided with a cap member 43 that is in the path of movement of a washer or flange 44 provided on the stem 8. This flange 44 is circular so that irrespective of the turning of the gear and stem the flange is at all times in position to engage the part 43 of the plunger 40 and depress the same as the plunger travels downward near the finish of its stroke. This carries the plunger 40 downward with it against the tension of the spring 42 and releases the pawl 22 whereupon continued operation of the block in the case does not result in actuation of the plunger. The stem 40 projects up through the block which is provided with a slot 45 for this purpose and the block is so formed as to allow freedom of movement of the spring 42 in expanding and contracting. This spring member may be of any type desired adapted for the purpose.

To fill the grease cup, the plunger is withdrawn therefrom as is indicated in Fig. 1 to a position where the threads thereof are out

of engagement with the threaded wall of the grease cup whereupon the latch 50, provided on the side of the device opposite the hinge 10, may be released and the entire case 5 and plunger turned outward on the hinge as is indicated in dotted lines in Fig. 7 exposing the cup and permitting its filling. Thereupon the case may be returned to position and the latch 50 secured and the plunger started in the threads in the cup or grease receptacle whereupon the device is ready for automatic operation.

From the foregoing description, it is evident that the device is comparatively simple 15 in form and is entirely automatic in operation, which operation is in conformity with and corresponding to the speed of operation of the locomotive rod, and further, that the rate of the grease by reciprocation of the 20 crank pin may be varied by alteration of the position of the buffers and varying the throw of the block.

Having thus briefly described my invention, what I claim is—

25 1. A lubricating device for locomotive rod pin connections comprising the combination with the rod and crank pin, of a cup for grease having a conduit opening to the bearing, a plunger provided with a stem adapted 30 to force the grease through the conduit, a casing above the grease cup through which the stem of the plunger extends, the casing having an upper and a lower chamber, a block in the said casing adapted to slide 35 back and forth therein by motion of the rod, and a pawl and ratchet device in the lower casing, a lever for operating the same, said lever having an end extending through the upper wall of the chamber into the block, a 40 single toothed gear rotated by the ratchet, a gear operated thereby, the gear being apertured to receive the plunger and adapted to rotate the same while allowing the plunger to move longitudinally therethrough.

45 2. A lubricating device for locomotive rod pin connections comprising the combination with the rod and crank pin, of a cup for grease having a conduit at the bottom opening to the bearing, the cup being counter-bored 50 providing an upper end of a greater diameter than the body, and the body therebelow being threaded, a threaded plunger for engagement therewith, a casing forming a cover for the cup and hinged to the rod 55 permitting the casing, when the plunger has been drawn from threaded relation and positioned within the said counter-bore, to be

turned to open the cup, a block slidable in the casing by movement of the rod, means for varying the extent of movement of the 60 block in the casing, a ratchet and gear device by rotation of which the said plunger is turned in the cup, said mechanism having a part connected with the block whereby movement of the same actuates the ratchet 65 and gear, and means for releasing the ratchet from operation by the block.

3. A lubricating device for locomotive rod pin connections comprising the combination with the rod and pin therefor, of a grease 70 cup carried by the rod, a plunger having threaded relation with the cup, a casing positioned over the cup and through which the stem of the plunger extends, a block free to slide in the casing by movement of the rod, 75 a pawl and ratchet mechanism carried in the casing actuated by movement of the block, means for releasing the pawl from the ratchet, and means on the plunger engaging said pawl releasing means as the plunger approaches its lowermost position in the cup.

4. A lubricating device for locomotive rod pin connections comprising the combination with the rod and pin therefor, of a grease 80 cup formed in the rod, the cup being counter-bored providing an upper end of greater diameter than the body, the body below the counter-bore being threaded, a threaded 85 plunger for engagement therewith, the length of the plunger being slightly less than 90 the depth of the counter bore whereby the plunger may be withdrawn from the threaded walls into the said counter bore, a feeding mechanism for the plunger, and a case for the mechanism, said mechanism including a 95 block reciprocated by the throw of the rod, and means connected therewith for turning the plunger, the case being adapted to expose the open end of the cup when the plunger has been withdrawn from threaded relation therewith.

5. A lubricating device for locomotive rod pin connections comprising the combination with a rod and pin therefor, of a grease cup carried by the rod, a plunger adapted for 105 threaded relation with the cup, a block adapted for limited reciprocal movement by movement of the rod, mechanism whereby said movement of the block causes rotation of the plunger relative to the cup, and means 110 causing cessation of rotation of the plunger actuated by the plunger on approaching the limit of its movement.

DEYO JONES.
